UNITED STATES PATENT OFFICE.

JOHN HAYS HAMMOND, JR., OF GLOUCESTER, MASSACHUSETTS.

TRANSMISSION SYSTEM FOR RADIANT ENERGY.

Application filed September 28, 1917, Serial No. 193,827. Renewed August 1, 1924.

Some of the objects of this invention are to provide an improved transmission system for radiant energy in which radiant oscillations are produced through the action of a high-vacuum, ionized gas or thermionic valve, or other suitable valve; to provide an improved system for the transmission of radiant energy which is operable to produce a series of high frequency electro-radiant oscillations through the action of a primary, high-vacuum, ionized gas or thermionic valve, and which is operable to periodically modify, through the action of suitable means, preferably, a secondary, high-vacuum, ionized gas or thermionic valve, or other suitable valve, and at a frequency above good audibility, the high frequency oscillations produced by the primary valve, to provide an improved receiving system for radiant energy, to provide a system for secretly transmitting signals, to provide an improved selective system for the transmission of radiant energy; and to provide other improvements as will hereinafter appear.

25 In the accompanying drawing:

Fig. 1 is a diagrammatic side elevation of a transmission system constructed in accordance with this invention; Fig. 2 is a diagrammatic side elevation of a receiving system constructed in accordance with this invention; and Figs. 3 and 4 are graphs explanatory of the operation of this improved system.

Referring to the drawing, and particularly to Fig. 1, which shows one form of transmission system constructed in accordance with this invention, an antenna 1 is grounded at 2 and includes an inductance coil 3 provided with an adjustable tap 4. The antenna 1 also includes a direct-current generator 5, or other source of high potential direct-current, arranged to give a suitable potential, for instance, from 500 to 1,000 volts. A variable condenser 6 is shunted 40 around the generator 5 to permit high frequency oscillations in the antenna 1 to pass around said generator 5.

For setting up electrical oscillations in the antenna circuit 1, 3, 2 any suitable valve, for instance, a high-vacuum, ionized gas or thermionic valve 15, may be provided. The illustrated valve is of well known construction and comprises a glass bulb 15', the interior of which is highly evacuated and contains a filament electrode 16, a grid electrode 17 and a plate electrode 18. The filament electrode

is arranged to be heated by a battery 19 operated through a rheostat 20. One end of the filament 16 is connected by a conductor 21 to the hereinbefore described adjustable tap 4. The grid 17 is connected by a conductor 21' to one side of a variable condenser 22, the other side of which is connected by a conductor 23 to the lower end of the inductance coil 3. An inductance coil 25 is shunted 60 around the variable condenser 22 to permit direct current to pass around the condenser 22 and to form a closed, oscillatory circuit 26 including the variable condenser 22. The plate electrode 18 is connected by a conductor 27 to the antenna circuit 1.

The elements of the transmission system thus far described may be operated to produce strong, continuous oscillations in the antenna circuit 1, 3, 2. The frequency of 75 these oscillations will depend mainly on the dimensions of the coil 3 and the constants of the antenna and ground 1—2 and only slightly on other local conditions such, for example, as the temperature of the filament 80 16 and the voltage of the generator 5.

For impressing upon the high frequency oscillations set up in the antenna circuit 1, 3, 2, as just described, periodic variations of amplitude, an auxiliary coil 30 is arranged so as to act inductively upon the hereinbefore described inductance coil 25, said auxiliary coil 30 thus forming the primary of a transformer 31 which includes inductance coil 25. Any suitable means 90 may be provided for setting up electrical oscillations of a suitable frequency in the auxiliary coil 30. In the form of the invention shown, a secondary, high-vacuum, ionized gas or thermionic valve 35 is one of the 95 elements used for this purpose. This secondary valve 35 is similar in construction to the primary valve 15 hereinbefore described, and includes a glass bulb 36 the interior of which is highly evacuated and contains a 100 filament electrode 37, a grid electrode 38 and a plate electrode 39. The filament electrode 37 is arranged to be heated by a battery 40 operated through a rheostat 41. The plate electrode 39 is connected by a conductor 44 105 to one pole of a direct-current, electric generator 45, or other source of a high potential direct-current, the other pole of which is connected by a conductor 46 to one end of the auxiliary coil 30. The other end of 110 the auxiliary coil 30 is connected by a conductor 47 to the grid electrode 38. A va-

riable condenser 50 is shunted around the generator 45 to permit high frequency oscillations to pass around the generator. A variable condenser 55 is connected on one side to the conductor 44 and upon its other side to the conductor 47 and completes a closed, oscillatory circuit 56 which includes the auxiliary coil 30. The auxiliary coil 30 is provided with an adjustable tap 57 which is connected by a conductor 58 to one end of the filament 37. The arrangement of the secondary valve 35 and its cooperating parts and circuits is such that when the generator 45 is in operation, strong, continuous, electrical oscillations will be produced in the auxiliary coil 30 having a frequency determined mainly by the inductance of the coil 30 and the capacity of the variable condenser 55, and these oscillations will be impressed upon the circuit of the primary valve 15 through the action of the transformer 31 and will cause corresponding periodical variations in the amplitude of the oscillations set up by the primary valve in the antenna circuit 1, 3, 2. A key 60 or other suitable signaling device may be arranged in any suitable position in the system, as for instance in the circuit 58 of the secondary valve 35.

In the operation of the entire transmission system shown in Fig. 1, the parts are preferably so proportioned and arranged that under the control of the primary valve 15 electrical oscillations having a frequency of, for instance, one million cycles per second, will be set up in the antenna circuit 1, 3, 2, and that oscillations of, for instance, thirty thousand cycles per second will be set up under the control of the secondary valve 35 in the closed, oscillatory circuit 56, which includes the auxiliary coil 30. As a result of these oscillations in the closed, oscillatory circuit 56, the closed, oscillatory circuit 26 is resonated approximately at the rate of thirty thousand oscillations per second.

The function of the secondary valve 35 is to impress through the transformer or coupling 31 a periodical potential fluctuation on the grid 17 of the primary valve 15, for instance, in the case noted a potential fluctuation of thirty thousand cycles per second. With the frequencies assumed above, this causes the amplitude of the oscillations of one million cycles per second set up in the antenna circuit 1, 3, 2, to fluctuate periodically at a frequency of thirty thousand cycles per second. The antenna circuit 1, 3, 2 will thus be caused to emit corresponding electro-radiant oscillations, having, for instance, an oscillation or wave frequency of one million cycles per second and a periodical amplitude variation frequency of thirty thousand cycles per second.

In Figs. 3 and 4, the passage of time is

plotted horizontally and the amplitude of the oscillations is plotted vertically, while the horizontal line 75 indicates zero potential. In Fig. 3 the electrical oscillations set up in and consequently radiated from the antenna circuit 1, 3, 2 under the control of the primary valve 15, uninfluenced by the secondary valve 35, are indicated diagrammatically by the full curved line 80, the time 81 between successive waves being, for instance, one one-millionth of a second. In Fig. 4 the full curved line 85 indicates the form of oscillations set up in and consequently radiated from the antenna circuit 1, 3, 2 while under the influence of both the primary valve 15 and the secondary valve 35, the time 81 between successive waves being, for instance, one one-millionth of a second, and the time 87 between periodic amplitude variations of the waves being, for instance, one thirty-thousandth of a second. For receiving the complex, electro-radiant oscillations emitted by the transmission system shown in Fig. 1, a receiving system of the form shown in Fig. 2 may be used. This system comprises an open aerial circuit 100 including an antenna 101 and an inductance coil 102 which is grounded at 103. The coil 102 forms the primary of a step-up transformer 105 including a secondary coil 106 which is connected in a closed, oscillatory circuit 107. The circuit 107 contains a variable condenser 108 and is arranged in a well known manner to control through a condenser 109 a primary, high-vacuum, gaseous detector 110, or any other suitable detector.

The primary detector 110 shown is similar in construction to the primary valve 15 hereinbefore described and includes a highly vacuumized glass bulb 110, a filament 111, a grid 112 and a plate 113. The filament 111 is arranged to be heated by a battery 114. The primary detector 110 is arranged to control a circuit including a battery 115 and an inductance coil 116, which is arranged in an oscillatory circuit 117 including a variable condenser 118. The coil 116 forms the primary of a transformer 120 which includes a secondary coil 121 connected in a secondary, closed, oscillatory circuit 125. The circuit 125 contains a variable condenser 126 and is arranged to control, through an inductive coil 127 and a condenser 128, a suitable secondary detector 130 which, as shown, is constructed as hereinbefore described.

The secondary detector 130 is arranged to control a circuit 135 including a battery 136, receiving telephones 137, or other receiving device, and a periodic interrupter 138. The interrupter 138 may be of any well known or suitable construction, and is rotated or operated to interrupt the circuit 135, 136, 137 at a uniform predetermined

rate within the range of audibility, for instance, 1,000 times per second, to render the unidirectional pulsations in the controlled circuit 135, 136 audible in the telephones 137, 5 as will hereinafter appear. A condenser 140 may be arranged in shunt around the telephones 137 or other receiving device to provide a closed, oscillatory circuit 141 which is preferably tuned to the frequency of the 10 interrupter 138 or of the beats which may be produced as will hereinafter appear in the circuit controlling the secondary detector 130 to build up selectively currents having the frequency of the interruptions produced in the circuit 135, 136 by the interrupter 138 or having the frequency of the 15 beats.

For impressing upon the circuit controlling the secondary detector 130, locally produced oscillations having a suitable frequency relatively to that of the oscillations produced in the circuit through the action of the primary detector 110, an auxiliary induction coil 150 is positioned in inductive 20 relation with the hereinbefore described coil 127 and is arranged in a closed circuit 151 energized by an electrical alternator 152 or other suitable source of electric oscillations.

30 In the operation of the receiving system shown in Fig. 2, when used in connection with the hereinbefore described transmission system shown in Fig. 1, the open, aerial circuit 100 is preferably tuned to respond to the high frequency of the transmitting system, for instance, one million oscillations per second, and the closed oscillatory circuit 107 is accordingly tuned to the same frequency. The primary, closed circuit 117, 35 which is controlled by the primary detector 110, is tuned to the secondary frequency of the transmission system, for instance, thirty thousand oscillations per second, and the secondary, closed circuit 125 controlling the secondary detector 130 is accordingly tuned to the last-named frequency. The circuit which includes the auxiliary coil 150 and the alternator 152 may be arranged to produce, for instance, thirty one thousand oscillations per second in the auxiliary coil 150.

Now when the electro-radiant oscillations or waves having a predetermined wave frequency of, for instance, one million cycles 55 per second, and a predetermined amplitude variation frequency of, for instance, thirty thousand cycles per second, as shown diagrammatically in Fig. 4, are received by the open, aerial circuit 100, corresponding oscillations are set up in the aerial circuit and in the closed, oscillatory circuit 107 controlled thereby and itself controlling the primary detector 110. This causes corresponding variations in the current normally 60 flowing through the circuit 115—116 con-

trolled by the primary detector 110 and produces unidirectional pulsations in the closed circuit 117 of the same frequency as the secondary frequency of the received waves, for instance, thirty thousand cycles per second. 70 The oscillations in the closed circuit 117 produce corresponding oscillations in the secondary, closed circuit 125 which act through the secondary detector 130 to correspondingly vary the current normally 75 flowing through the controlled circuit 135, 136, 137, 138 to produce unidirectional impulses of a frequency of thirty thousand cycles per second. These impulses being of a frequency above audibility cannot be heard 80 in the telephones 137 except as the result of the operation of the interrupter 138 or of the oscillatory circuit 151.

When the interrupter 138 is stationary and in a closed position, completing the circuit through the detector 130 and telephones 137, and the alternator 152 is in operation to produce oscillations of a frequency of, for instance, thirty-one thousand cycles per second in the auxiliary coil 150, these oscillations act inductively upon the coil 127 to produce corresponding oscillations in the circuit containing the coil 127 and controlling the secondary detector 130. The oscillations combine with the oscillations of 95 thirty thousand cycles per second in the circuit including coil 127 and produce therein beats having a frequency of 1,000 cycles per second. These beats act through the secondary detector 130 to cause corresponding 100 unidirectional impulses of one thousand cycles per second in the circuit 135, 136, 137 controlled by the secondary detector 130, and these impulses are audible in the telephones 137.

If, instead of the telephones 137, some other receiving device which does not function to produce audible sounds, such, for instance, as a relay, should be employed, it would not be necessary to use the interrupter 138 or the oscillatory circuit 151. The closed, oscillatory circuit 151, however, might be utilized for the purpose of producing amplification of the impulses in the circuit controlled by the secondary detector 115 130 and a consequent increase in effectiveness in controlling a relay or other receiving or signaling instrument.

What I claim is:

1. A system of radio transmission, comprising an aerial circuit including a source of current, means including a thermionic valve cooperating with said source to produce electrical oscillations in said circuit, and means including a thermionic valve arranged to impress periodic amplitude variations upon said oscillations.

2. A system of radio transmission, comprising an aerial circuit including a source of high potential direct current and an in-

ductance, a condenser shunted around said source, means including a thermionic valve cooperating with said source and said inductance for producing electric oscillations in 5 said circuit, said valve including ionizing means variably connected to said inductance, and means inductively connected to said first-mentioned means for impressing periodic amplitude variations upon said oscillations.

3. In a system for selective radio transmission, a transmitting system comprising means including a thermionic valve for producing high frequency electric oscillations, 15 means for impressing upon said oscillations periodic amplitude variations of a frequency above good audibility, and a receiving system including cooperating receiving circuits tuned respectively to the frequencies of said 20 oscillations and said variations and provided with an interrupter acting at an audible frequency.

4. In a system for selective radio transmission, a transmitter comprising means for 25 producing high frequency oscillations, including a thermionic valve having plate and grid circuits connected in inductive relation, an oscillatory circuit connected in said grid circuit and means for impressing thereon 30 oscillations of a frequency above good audibility and thereby causing said valve to produce oscillations modulated in accordance with said second mentioned oscillations, said last mentioned means including a thermionic 35 valve and a closed oscillatory circuit connected therewith and inductively coupled with the first mentioned oscillatory circuit.

5. In a system for selective radio transmission, a transmitter comprising means for 40 producing high frequency oscillations, including a thermionic valve having plate and grid circuits connected in inductive relation, an oscillatory circuit connected in said grid circuit and means for impressing thereon 45 oscillations of a frequency above good audibility and thereby causing said valve to produce oscillations modulated in accordance

with said second mentioned oscillations, said last mentioned means including a thermionic valve and a closed oscillatory circuit connected therewith and inductively coupled with the first mentioned oscillatory circuit, and signalling means incorporated in the external circuit of said last mentioned valve for selectively causing generation of said 50 lower frequency oscillations.

6. A system of selective radio transmission comprising a thermionic oscillator for producing high frequency electrical oscillations, said thermionic oscillator having included in its grid circuit a closed oscillatory circuit adapted to control the amount of current flowing in said grid circuit, and a second thermionic oscillator adapted to oscillate at 60 a lower but supersonic frequency and inductively coupled to said closed oscillatory circuit to control at said lower frequency the amount of current flowing in said grid circuit and thereby the amplitude of the high 65 frequency oscillations produced by said first 70 mentioned thermionic oscillator.

7. A system of selective radio transmission comprising a thermionic oscillator for producing high frequency electrical oscillations, said thermionic oscillator having included in its grid circuit a closed oscillatory circuit adapted to control the amount of current flowing in said grid circuit, a second thermionic oscillator adapted to oscillate at a lower but supersonic frequency and inductively coupled to said closed oscillatory circuit to control at said lower frequency the amount of current flowing in said grid circuit and thereby the amplitude of the high 75 frequency oscillations produced by said first 80 mentioned thermionic oscillator, and signalling means incorporated in said last mentioned oscillator circuit for selectively causing generation of said low frequency oscillations and thereby the modulation of said 85 high frequency.

Signed this 25th day of Sept., 1917.
